ARTHUR M. WATKINS, WILLIAM E. BEWLEY, AND WILLIAM J. MOORE, PARTNERS.

SELF-PROPELLED FLOOR-PLANER.

1,305,734.

Specification of Letters Patent. Patented June 3, 1919.

Application filed August 15, 1917. Serial No. 186,283.

To all whom it may concern:

Be it known that I, WILLIAM J. MOORE, a citizen of the United States, and resident of Plainfield, county of Union, and State of 5 New Jersey, have invented certain new and useful Improvements in Self-Propelled Floor-Planers, of which the following is a specification.

My invention relates more particularly to 10 a type of floor-planer adapted to be used for planing wooden floors, ship decks or similar flat surfaces over which the machine is adapted to be propelled. Preferably a rotary cutter head is employed and adapted 15 to be rotated at high speed to plane the surface, the cutter head being of the usual type employed in planing machines.

One object of my improved machine, is to 20 provide means for readily throwing the cutter head into and out of contact with the floor surface without disturbing the relations between the cutter and the motor drive.

Another object is to utilize the same motor 25 which drives the cutter head as a means for propelling the planer over the floor. This is accomplished by introducing gear connections between the motor and the drive or propelling wheels adapted to reduce the speed whereby the planer is propelled over 30 the floor at the most efficient speed for planing with this type of cutter head. A suitable clutch is preferably installed in the connections between the motor and the propelling wheels whereby the latter may be 35 connected and disconnected at the will of the operator.

It is necessary that a machine of this character should be capable of being steered or turned about over the surface being operated upon. For this purpose, I preferably 40 mount the drive or propelling wheels in such a manner that they may be turned for steering the planer.

In attaining these objects, I have produced 45 a floor-planer which is highly efficient and adapted for high speed operation and can readily be manipulated to cover the surface being planed.

One form of my improved self-propelled 50 floor planer is shown in the accompanying drawings in which Figure 1 is a side elevation of the machine; Fig. 2 is a top plan view of the machine; Fig. 3 is a plan view with the upper portion of the machine re- 55 moved on section line 3—3 of Fig. 5; Fig.

4 is a view of the rear end of the machine, some parts being broken away; Fig. 5 is a longitudinally vertical section on the line 5—5 of Fig. 3; Fig. 6 is a sectional detail of the adjustment for the cutter head bracket 60 substantially on the line 6—6 of Fig. 7; Fig. 7 represents a cross-section substantially on the line 7—7 of Fig. 6; Fig. 8 is a sectional detail of the gib adjustment for the dovetail slide and Fig. 9 is a separate 65 view of the drive wheels and steering connections, the section being taken on the line 9—9 of Fig. 4.

Referring to the drawings, 1 represents the main frame of the machine which may 70 be of any suitable form or construction, but preferably is a hollow box-like casting open on the lower side and closed on the top side. An electric motor 2 is preferably mounted on top of the frame 1 and secured thereto 75 by suitable bolts 3. The motor shaft 4 is provided at one end with a sprocket wheel 5 secured thereto. A similar sprocket wheel 6 is secured near one end of a shaft 7 extending transversely of the main frame 1 and 80 revolubly mounted therein. A suitable sprocket chain 8 connects the motor shaft 4 with the shaft 7 so that the latter will be driven at the speed of the motor. Each end of the shaft 7 is provided with pulley wheels 85 9 over which belts 10 pass for driving the cutter head. The cutter head 11 is mounted at the front end of the machine and the cutter head shaft 12 is provided with small pulleys 13 at each end thereof over which the 90 belts 10 are adapted to pass, the relation between the pulleys 9 and 13 preferably being such that the cutter head 11 will rotate at a speed several times greater than the speed of the motor. Obviously the proportions 95 between the pulleys and sprocket connections with the motor may be varied to give any desired relations as to speed.

It has been found desirable to provide means for adjusting the position of the cutter head 11 with respect to the frame 1 and the floor or other surface to be planed. To accomplish this, the main frame 1, at the front end thereof, is preferably provided with a ledge or extension 14, the outer face 100 of which is planed off and provided with two vertical T slots 15 (see Figs. 6 and 7). A bracket member 16 is mounted on the face of the ledge 14 and held in place by T-bolts 17 and 18. The bracket member 16 105

is provided with forwardly projecting arms 19 provided with bosses 20 bored out to form bearings for the cutter head shaft 12. The T-bolts 17 and 18 are preferably of special 5 construction as indicated in Figs. 6 and 7. The head of the upper bolt 17 is preferably bored out and threaded to take the threads of a bolt 21 while the lower T-bolt 18 is bored out smooth for the passage of the 10 lower end of the bolt 21, the latter being provided with a head 22 adapted to engage the lower face of the T-slot ledge 14. A washer 23 engages the upper surface of the ledge 14 and the bolt is held in place in 15 the T slot by a suitable nut 24 which is preferably pinned to the bolt 21 as indicated at 25. By this arrangement, it will be seen that when the nuts on the T-bolts 17 and 18 are loosened, the cutter head bracket 16 20 can be shifted up or down with relation to the main frame 1 by turning the bolts 21 with a wrench applied to the nuts 24. In this adjustment, the threaded T-bolt 17 will be forced to move up or down in the T-slot, 25 since the bolt 21 is relatively fixed in position, the lower T-bolt 18 merely sliding on the bolt 21. After an adjustment has been made, the nuts on the bolts 17 and 18 can be turned up to solidly clamp the bracket 30 to the ledge 14.

In order that the belts 10, for driving the cutter head 11, may be tightened, I preferably provide at each side of the machine a swinging arm 26 pivoted at 27 to the side 35 wall of the main frame of the machine and provided at its forward or free end with an idler pulley 28 adapted to engage the upper surface of the belt 10 substantially as indicated in Fig. 1 of the drawings. A slotted 40 lug 29 preferably extends laterally from the arm 26 and a bolt 30 passes through the slot, the nut thereof being adapted to clamp the arm 26 in its adjusted position. Two of these idler pulley arms 26 are provided, one 45 for each of the belts 10 as will be seen in Figs. 2 and 3 of the drawings.

The front end of the floor-planer is preferably mounted upon and supported by a pair of wheels 31 carried upon a shaft 32 50 having bearings in the side walls of the main frame 1 substantially as indicated in Fig. 3 of the drawings.

The rear portion of the machine is supported by a pair of wheels which are preferably propelling or driving wheels which 55 may be connected to the motor in any suitable or preferred manner. In the present instance, the shaft 7 which as previously explained, is driven at the same speed as 60 the motor, is provided with a gear pinion 33 secured thereto inside of the frame 1 substantially as indicated in Fig. 3 of the drawings. The pinion 33 meshes with a large gear 34 loosely mounted upon a shaft or 65 rod 35 mounted transversely of the main

frame 1 of the machine. The gear 34 is provided with a laterally extending hub upon which a sprocket pinion 36 is secured. A sprocket chain 37 passes over the sprocket pinion 36 and over a large sprocket gear 38 70 revolvably mounted upon a shaft 39 pivoted in the side walls of the main frame 1 near the forward end thereof above the front wheels (see Figs. 3 and 5 of the drawings). The shaft 39 is revolvably mounted in suitable bearings in the side walls of the frame 1 and has keyed thereto a clutch cone 40 adapted to engage a cone socket in the hub 41 of the sprocket gear 38. It will be understood that the cone member 40, while keyed 80 to the shaft 39, is slidable longitudinally thereon in order that the clutch may be engaged and disengaged. A fork 42 provided with the usual lugs or pins for engaging an annular groove in the cone member 85 40 is provided and secured to a rock shaft 43 extending longitudinally of the main frame 1 and pivotally mounted therein substantially as indicated in Figs. 3 and 5 of the drawings. The rear end of the rod or 90 rock shaft 43 is preferably provided with an upstanding rock arm or hand lever 44 keyed to the shaft 43 so that the latter may be rocked at will by the operator to throw the clutch in and out and thereby connect 95 and disconnect the driving wheels from the motor. The shaft 39 is also provided with a sprocket pinion 45, secured thereto, over which a sprocket chain 46 passes. The sprocket chain 46 also extends over a large 100 sprocket gear 47 revolvably mounted upon the fixed rod or shaft 35 upon which the gear 34 revolves. The sprocket wheel 47 is preferably provided with a laterally extending hub or sleeve 48 extending through and having bearing in the main frame 1 and provided at its outer end, which projects through the wall of the frame 1 with a sprocket pinion 49 secured thereto and connected by means of a sprocket chain 50 with 105 a similar pinion 51 substantially as shown in Figs. 3 and 5 of the drawings.

The sprocket pinion 51 is secured to a shaft 52 pivotally mounted at the rear of the machine in bearings 53 and 54 projecting 115 upward from a knee bracket 55 slidably mounted upon the rear wall of the main frame 1. The bearing 54 is located substantially at the middle of the machine and the shaft 52 is provided with a pair of oppositely faced bevel or miter gears 56 and 57 secured thereto. The gears 56 and 57 are on opposite sides of the bearing 54 and are adapted to engage respectively similar miter gears 58 and 59, each secured to the upper 120 end of a short vertically extending shaft. The two vertically extending shafts 60 and 61 extend through bearings in the shelf portion 62 of the knee bracket and have secured to their lower ends the miter gears 125 130

63 and 64 respectively, adapted to mesh with corresponding miter gears 65 and 66 secured respectively to the drive or propelling wheels 67 and 68 which it will be understood 5 act as a support for the rear portion of the floor planer and are adapted to propel it over the floor.

In order that the floor planer may be steered, any suitable steering mechanism 10 may be employed, but preferably, the drive wheels 67 and 68 are mounted upon shafts 69 and 70 rotatably supported in forks or yokes 71 and 72 pivotally mounted upon the respective shafts 60 and 61, which as 15 previously explained, carry the miter gears through which power is transmitted from the motor to the driving wheels. The yokes or forks 71 and 72 have bearing bosses 73 and 74 engaging bearing surfaces on the 20 lower side of the shelf portion 62 of the rear slide bracket 55 as will be seen in Figs. 4 and 5 of the drawings. Each of the forks 71 and 72 is preferably provided with a rearwardly projecting lug 75 and 76 respectively, which are connected together by a 25 transversely extending link or bar 77, so that both forks may be moved simultaneously as is required for steering. A steering rod 78 is preferably pivoted by means of a stud 30 bolt 79 to the underside of the shelf portion 62 of the knee bracket (see Fig. 5). The steering rod 78 extends rearward and upward and is preferably provided with a pair of handles 80 which may be gripped by the 35 hands of the operator for steering the floor planer when in operation. An eye bolt 81 is attached to the steering rod 78 and passes through a hole in the bar 77 being held in place by a suitable nut 82, the arrangement 40 being such that by rocking the steering rod 78 laterally, the bar 77 will be moved and the latter through its connection with the lugs 75 and 76 of the steering forks will turn the steering and driving wheels 67 and 68 45 for steering the floor planer over the surface being planed.

It will be observed that the entire machine is supported upon the two pairs of wheels, the rear wheels being propelling as well as 50 steering wheels. The front wheels 31 are located back of the cutter head 11 as indicated in the drawings (see Fig. 5) and obviously, if the main frame of the machine is rocked about the front wheels as a fulcrum, the cutter head can be raised or lowered with 55 respect to the surface being planed. It is desirable to do this without disturbing the adjusted relations between the cutter head and the motor drive and to do it quickly. In 60 order that this may be accomplished satisfactorily, the knee bracket 55, which as previously explained, forms the bearing support for the steering and drive wheel mechanism is slidably mounted upon the rear wall of 65 the main frame 1 of the machine by a dove-

tail slide 83 substantially as indicated in Figs. 3 and 5 of the drawings. I preferably provide a slidable take up member or gib 84 which may be of the usual or any preferred construction, preferably wedge shaped and 70 adapted to be moved longitudinally of the dovetail in order to take up lost motion between the parts. The gib 84 is preferably adjustable by means of a screw 85 taking 75 into a threaded hole 86 in the knee bracket 55 substantially as indicated in the detailed section shown in Fig. 8 of the drawings. Lock nuts 87 are provided for holding the gib in adjusted position. The relation between the knee bracket 55 and the rear portion 80 of the main frame 1 is regulated by sliding the knee bracket up and down in the dovetail slide. This is preferably accomplished by a screw 88 provided with coarse or long pitch threads at 89 taking 85 into a threaded hole 90 in the knee member 55 as indicated in Fig. 5 of the drawings.

A lug 91 preferably extends rearward from the middle of the main frame 1 and is bored out to permit the upper portion 92 of 90 the screw 88 to pass therethrough, the portion 92 being preferably slightly larger in diameter as indicated in Fig. 5 of the drawings. The upper end of the screw 88 is provided with a star or hand wheel 93 pinned 95 to the screw so that the latter may be turned to raise or lower the main frame with respect to the knee bracket 55. A suitable collar 94 is secured to the screw below the bearing lug 91 for the purpose of maintaining the screw 100 88 in proper position and permitting the screw to remain stationary while the knee bracket 55 is made to slide up and down in the dovetail in the manner indicated. By having long pitch threads on the screw 88, 105 it will be understood that the adjustment may be quickly made by turning the hand wheel 93. Obviously, if desired, the hub of the hand wheel may be provided with graduations in the usual manner to serve as an 110 index in adjusting the position of the main frame and hence of the cutter head 11. It will be understood that in adjusting the frame 1 with respect to the knee bracket 55 by means of the screw 88, the main frame 1 115 will be rocked about the front wheels as a fulcrum, thereby raising or lowering the cutter head 11. In this way, means is provided for quickly adjusting the depth of cut of the cutter head as well as permitting the operator 120 to lift the cutter head entirely out of planing action without stopping the rotation thereof or disturbing the relations or adjustments which may have been made by means of the screws 21 at the front of the 125 machine.

Sufficient slack is left in the drive chain 50 to permit the slide movement between the main frame 1 and the knee bracket 55 in adjusting the relations just described, and if de- 130

sirable, suitable idler take up mechanism may be provided. In order to take up any slack in the drive chains 37 and 46, I preferably provide idler wheels mounted upon suitable rock levers. To take up the slack in the driving chain 37, an idler wheel 95 is pivotally mounted upon a lever 96 and adapted to engage the chain 37 substantially as indicated in Fig. 3 of the drawings. The lever 96 is preferably pivotally mounted upon the shaft 35 and is bent laterally at 97, and extends through an opening 98 in the side wall of the main frame 1. The lever 96 is again bent to parallel the side of the frame 1 and provided with a slotted lug 99 through which a bolt 100 passes, a nut 101 being provided for clamping the lever in adjusted position. A similar arrangement is provided for the chain 46 as will be seen in Figs. 3 and 5 of the drawings. An idler wheel 102 is adapted to engage the upper surface of the chain 46 and is rotatably supported upon a lever 103 pivoted on the shaft 39 and bent laterally at 104 to extend through an opening 105 in the side wall of the main frame 1. The outer end is bent parallel with the main frame and provided with a similar slotted lug 106, a bolt and nut 107 being provided for clamping the lever 103 in adjusted position.

In operating the machine, it will be understood that the cutter head should be adjusted by means of the screws 21 to rotate at the required angle with relation to the main frame 35 of the machine or parallel with the surface to be planed. Obviously, this ordinarily should place the shaft 12 of the cutter head parallel to the axis of the front wheels. After this adjustment has been made, the slide bracket 16, supporting the cutter head, is clamped in position by tightening the nuts of the T-bolts 17 and 18. When this adjustment has been satisfactorily completed, the belts 10 are properly tightened by adjusting the idler pulleys 28 and clamping the arms 26 by means of the bolts 30. Similarly, if there is any slackness in the chains 37 and 46, it may be taken up by adjusting the respective idler wheels 95 and 102 and clamping the levers 96 and 103 as hereinbefore described.

The rheostat and motor control box 108 may be attached to the handle bars 80 by means of suitable bolts or screws 109, as indicated in Fig. 1 of the drawings, and a suitable wire or cable connection (not shown) made between the box and the motor. This connection need not be fully described because it is well known to those skilled in the art.

To start planing, the cutter head is preferably lifted out of contact with the surface by turning the screw 88 by means of the hand or star wheel 93, thereby rocking the main frame about the front wheels as a fulcrum.

In this position, the clutch 40 may be disconnected by means of the handle 44 and the motor started from the starting box 108. The operator then lowers the cutter head into contact with the surface to be planed, and by means of the star wheel 93 adjusts the depth of cut. The clutch 40 is then closed by means of the handle 44 and the planer will be propelled by the driving or propelling wheels 67 and 68, power being derived from the motor 75 through chain and gear connections hereinbefore described. The planer is steered from the handle 80 through the connection of the steering rod 78 and the link 77 connecting the yokes 71 and 72, which as previously described, are adapted to turn the driving wheels 67 and 68 for steering the planer.

While I have described one form of my improved self-propelled floor planer, it will be understood that I do not wish to be limited to the specific details of construction, for obviously, various modifications may be made in the construction and arrangement of the parts to obtain the results specified without departing from the spirit and scope of the invention.

I claim:

1. In a self propelled floor planer the combination of a body frame, a motor 95 mounted thereon, a pair of wheels supporting said frame near the front end, a rotary cylindrical cutter in front of said wheels and connected to be driven by said motor, a pair of wheels supporting the rear end of the frame, said rear wheels being propelling and steering wheels adapted to be driven by said motor, means for adjusting said body frame relative to said driving wheels thereby rocking said frame on said front wheels to 100 raise and lower said cutter, and a clutch for throwing said driving wheels into and out of gear with said motor.

2. In a self propelled floor planer the combination of a body frame, a motor mounted 110 thereon, a rotary cutter head mounted on the front end of said frame transversely thereof, connections whereby the cutter head is driven continuously by said motor, a pair of wheels located back of said cutter 115 head for supporting the front end of said body frame, a pair of driving wheels supporting the rear end of said frame adapted to be driven by said motor, means for mounting said driven wheels whereby they may be 120 turned for steering, a clutch for throwing said driving wheels into and out of gear with said motor and means for adjusting said body frame relative to said driving wheels, said frame being rocked on the front 125 wheels as a fulcrum thereby raising and lowering said cutter for controlling the depth of cut.

3. In a self propelled floor planer the combination of a body frame, a motor mounted 130

- thereon, a cutter head adapted to be continuously driven by said motor, a pair of wheels on a fixed axle for supporting the front end of said frame, a pair of wheels 5 for supporting the rear end of said frame, said rear wheels being driving wheels adapted to be driven by said motor, means for mounting said driving wheels whereby they may be turned for steering and means 10 for adjusting the rear end of said body frame vertically relative to said propelling wheels thereby rocking said frame about the front wheels as a fulcrum to raise and lower said cutter and to control the depth of cut.
- 15 4. In a self propelled floor planer the combination of a body frame, a motor mounted thereon, a cutter head adapted to be continuously driven by said motor, a pair of wheels on a fixed axle for supporting the 20 front end of said frame, a pair of wheels for supporting the rear end of said frame, said rear wheels being driving wheels adapted to be driven by said motor, a fork for each driving wheel adapting said wheels to be turned 25 for steering, means for connecting said forks together and to a steering handle, a slide bracket whereon said steering wheels and steering handle are mounted, said bracket being vertically slidable on the end of said 30 body frame and means for adjusting the body frame relative to said bracket.
5. In a self propelled floor planer the combination of a body frame, a motor mounted thereon, a cutter head adapted to be 35 continuously driven by said motor, a pair of wheels on a fixed axle for supporting the front end of said frame, a pair of wheels for supporting the rear end of said frame, said rear wheels being driving wheels 40 adapted to be driven by said motor, a fork for each driving wheel adapting said wheels to be turned for steering, means for connecting said forks together and to a steering handle, a slide bracket whereon said steering 45 wheels and steering handle are mounted, said bracket being vertically slidable on the end of said body frame and a screw provided with a hand wheel for adjusting the body frame relative to said bracket, whereby 50 said frame is rocked about the front wheels as a fulcrum to regulate the depth of cut of said cutter.
6. In a self propelled floor planer the combination of a body frame, a motor 55 mounted thereon, a cutter head adapted to be continuously driven by said motor, a bearing member mounted for vertical adjustment on the front of said frame and adapted to support said cutter, means permitting said member to be adjusted and 60 fixedly clamped to said frame, a pair of wheels on a fixed axle for supporting the front end of said frame, a pair of wheels for supporting the rear end of said frame, said rear wheels being driving wheels adapted to be driven by said motor, means for mounting said driving wheels whereby they may be turned for steering and means for adjusting the rear end of said body frame vertically relative to said propelling wheels 65 thereby rocking said frame about the front wheels as a fulcrum to raise and lower said cutter and control the depth of cut.
7. In a self propelled floor planer the combination of a body frame, a motor 70 mounted thereon, a pair of wheels mounted in said frame for supporting the front end thereof, a cylindrical cutter rotatably mounted in front of said wheels and adapted to be continuously driven by said motor, a pair of wheels supporting the rear end of said frame, said rear wheels being driving and steering wheels, a slide bracket in which said rear wheels are mounted, means for adjusting the relation of the frame and 75 said bracket, whereby said frame is rocked on the front wheels as a fulcrum to raise and lower said cutter and regulate the depth of cut, means connecting said driving and steering wheels to be driven by said motor 80 while permitting said adjustment and means for simultaneously turning said driving wheels for steering the planer.
8. In a self propelled floor planer the combination of a body frame, a motor 85 mounted thereon, a pair of wheels mounted in said frame for supporting the front end thereof, a cylindrical cutter rotatably mounted in front of said wheels and adapted to be continuously driven by said motor, a bearing member supporting said cutter mounted for vertical adjustment on the front end of said frame, a pair of wheels supporting the rear end of said frame, said rear wheels being driving and steering 90 wheels, a slide bracket in which said rear wheels are mounted, a hand-wheel screw for adjusting the relation between the frame and said bracket, whereby said frame is rocked on the front wheels as a fulcrum to 95 raise and lower said cutter and regulate the depth of cut, driving connections between the motor and said driving wheels adapted to permit said adjustment between the frame and said bracket, a clutch for connecting 100 and disconnecting said driving wheels with said motor and handle connections for turning said rear wheels for steering the planer.
